UNITED STATES PATENT OFFICE

NICHOLAS J. PREVITE, OF JACKSON HEIGHTS, NEW YORK

PAINT BRUSH AND GUARD

Application filed February 3, 1930, Serial No. 425,379. Renewed October 21, 1932.

This invention relates to new and useful improvements in a paint brush and guard.

The invention has for an object the provision of a device of the class mentioned which is of simple durable construction, dependable in use and efficient in action, and which can be manufactured and sold at a reasonable cost.

The invention proposes a body portion supporting bristles at one side and formed with passages from the vicinity of the bristle roots to a valve seat connecting with a passage discharge at the sides of said body, a removable flared guard encircling said body portion immediately to the rear of the inner ends of said bristles and formed with rear edges turned inwards and engaging in packing grooves formed in said body so that said discharge passages terminate within said guard, means for latching said guard against displacement, and means for restricting passage thru said discharge when the guard is removed.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a side elevational view of a device constructed according to this invention.

Fig. 2 is a plan view of Fig. 1.

Fig. 3 is a fragmentary vertical sectional view taken on the line 3—3 of Fig. 2.

Fig. 4 is a fragmentary vertical sectional view taken on the line 4—4 of Fig. 2.

Fig. 5 is a fragmentary vertical sectional view taken on the line 5—5 of Fig. 1.

Fig. 6 is a fragmentary horizontal sectional view taken on the line 6—6 of Fig. 1.

Fig. 7 is a fragmentary horizontal sectional view taken on the line 7—7 of Fig. 1.

The paint brush and guard consists of a body portion 10 supporting bristles 11 at one end thereof and formed with passages 12 extending from the vicinity of the bristle roots 13 to a valve seat 14 connecting with a passage 15 discharging at the sides 16 of the said

body 10, a removable flared guard 17 encircling said body portion 10 immediately to the rear ends of the bristles 11 and formed with rear edges 18 turned inwards and engaging in packing grooves 19 formed in the body 10 so that said discharge 15 terminates within the guard 17, means for latching said guard against displacement, and means for restricting passage thru said discharge 15 when the guard 17 is removed.

The body portion 10 includes a handle 20 for the manual manipulation of the brush. Some of the passages 12 are inclined and others vertical, but all terminate at the valve seat 14. The guard 17 is made of two guard sections 17^a and 17^b hinged at one side 21 and held together at the other side with a catch in the form of a screw 22. A water-proof strip 23 is arranged over the hinge 21 for rendering the joint water tight. The screw 22 constitutes the means for latching the guard against displacement. The free ends of the guard sections 17^a and 17^b overlap as indicated in Fig. 7 and a rubber packing strip 24 is secured upon one of the ends so as to engage against the other end and form a water tight joint when the guard is in place. The screw 22 extends through the overlapped ends of the guard section 17^a, the rubber packing strip 24, and the guard section 17^b.

The packing grooves 19 are formed of rubber strips 25 inserted in grooves 26 formed in the body portion 10. These grooves are of V shape in side elevation as may be seen from an inspection of Fig. 1. The purpose of the V shape is to add rigidity to the guard, eliminating any other means for its supporting. In addition, the V shape of the guard provides a low point to which the liquid will run, that is, paint during the use of the brush and upon a subsequent dipping of the brush into the pot of paint, the paint will flow back into the pot.

The means for restricting passage thru the discharge 15 when the guard 17 is removed, comprises a valve head 28 engageable upon the seat 14 and slidably mounted in the body portion 10 and connected with a bell crank 29 pivoted intermediately at 30. In Fig. 5 the valve is shown in its retracted position. A

tension spring 31 acts between one of the arms of the bell crank 29 and the body portion 10 for normally urging the valve head upon its seat. This urge is restrained by a pin 32 pivotally connected with the other arm of the bell crank 29 and extending thru an aperture in the body portion 10 and normally held depressed by the inturned edge 18 of the guard when the guard is in position upon the body member.

The paint brush may be used in a customary manner for painting the interior of a room or other structure. When the ceiling is painted, it is desirable that the guard be arranged upon the paint brush to collect any paint running downwards. Excess paint from the bristles of the brush may pass thru the passages 12 and discharge at 15 into the guard. Paint running down the sides of the bristles will also discharge into the guard. When the guard is next dipped, this paint will run back into the main body of paint. When walls or the like are painted, the guard should be removed since it is of no avail in this particular operation. Upon removal of the guard the valve 28 automatically assumes a closed position upon the seat 14. This prevents the passage of paint from the bristle roots down along the sides of the brush.

It is to be understood that the brush may be of any size, shape or form.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A paint brush and guard, comprising a body portion supporting bristles at one end thereof and formed with passages from the said end of said body to a valve seat, said valve seat connecting with a passage discharging at the sides of said body, a removable flared guard encircling said body portion below said passage discharge and formed with rear edges turned inwards and engaging in packed grooves formed in said body means for latching said guard against displacement, and means for preventing passage thru said discharge when the guard is removed.

2. A paint brush and guard, comprising a body portion supporting bristles at one end thereof and formed with passages from the said end of said body to a valve seat, said valve seat connecting with a passage discharging at the sides of said body, a removable flared guard encircling said body portion below said passage discharge and formed with rear edges turned inwards and engaging in packed grooves formed in said body means for latching said guard against displacement,

and means for preventing passage thru said discharge when the guard is removed, said guard being made of two sections hingedly connected at one side.

3. A paint brush and guard, comprising a body portion supporting bristles at one end thereof and formed with passages from the said end of said body to a valve seat, said valve seat connecting with a passage discharging at the sides of said body, a removable flared guard encircling said body portion below said passage discharge and formed with rear edges turned inwards and engaging in packed grooves formed in said body, means for latching said guard against displacement, and means for preventing passage thru said discharge when the guard is removed, comprising a valve head engageable on said seat and slidably mounted in the body portion, a bell crank pivoted intermediate of its ends and connected to said valve head, means acting between one of the arms of the bell crank and the body portion for normally urging the valve head upon its seat, and a pin connected with the other arm of the bell crank normally extending from the side of the body portion through one of said packed grooves in the closed position of the valve so that the inturned edge of the guard will hold the pin in non-extended position and thus hold the valve open.

4. A paint brush and guard, comprising a body portion supporting bristles at one end thereof and formed with passages from the said end of said body to a valve seat, said valve seat connecting with a passage discharging at the sides of said body, a removable flared guard encircling said body portion below said passage discharge and formed with rear edges turned inwards and engaging in packed grooves formed in said body, means for latching said guard against displacement, and means for preventing passage thru said discharge when the guard is removed, comprising a valve head engageable on said seat, means for normally urging said valve upon the seat, and a pin connected with said latter means and normally extending from the side of the body portion through one of said packed grooves in the closed position of the valve so that the inturned edge of the guard will hold the pin in non-extended position and thus hold the valve open when the guard is in operative position on said body portion.

In testimony whereof I have affixed my signature.

NICHOLAS J. PREVITE.
